PASTE APPLYING DEVICE

John Crighton and Robert John Alexander Chandler, London, England, assignors to American Machine & Foundry Company, New York, N. Y., a corporation of New Jersey

Application November 28, 1936, Serial No. 113,244
In Great Britain November 30, 1935

5 Claims. (Cl. 131—43)

This invention relates to paste applying apparatus of the type adapted to apply paste to the margin of a running web such as the wrapper in a continuous cigarette rod making machine.

- 5 The object of the invention is to provide an improved construction of pasting apparatus suitable for use with soft pastes such relatively soft starch paste not requiring milling but necessitating a pressure feed.
- 10 The invention consists in an apparatus for applying paste to a moving surface, such as the wrapper web of a cigarette rod machine, comprising a paste pot or container having a paste feeding roll located in the outlet and adapted to transfer paste directly to the paste applying disc, and means for applying pressure to the paste to feed it to the roll.
- 15

The roll may be provided with a concavity or contour complementary to the paste applying disc and the surfaces adjacent the concave part are bevelled off whereby any paste collecting on the sides of the roll is prevented from transference to the pasting disc.

Further features of the invention will be hereinafter described and defined in the claims.

In the accompanying drawings which illustrate an apparatus suitable for applying paste to a cigarette web:

Figure 1 is a front view of a paste applying apparatus according to the invention the paste applying disc being omitted;

Figure 2 is a sectional elevation; and

Figure 3 is a partial view of the feed roll and the paste applying device.

35 Figure 4 is a partial front view to a larger scale showing the mounting of the feed roll.

Figure 5 is a part sectional elevation showing the unitary structure of the apparatus according to the invention.

40 In carrying the invention into effect according to one convenient mode as applied to a pasting device for applying paste to the running wrapper web of a cigarette rod machine, a paste pot or box 10 is provided open at the upper end and

45 having a rear wall 11 which slopes toward the outlet 12. The outlet accommodates a paste transferring or feed roll 13 having a smooth periphery which roll is located partly within the box. The roll is preferably arranged so that as

50 large a surface of the roll as convenient is in contact with the paste in the box so as to impart movement to the paste and insure a uniform feed or flow to the roll. The roll 13 is mounted for rotation upon a shaft 16 located in suitable

55 bushings 16a carried by or formed in the side

walls 14 of the box adjacent the outlet 12. The ends of the roll are in close working contact with the surfaces 15 of the walls 14 so that substantially no paste can exude at said ends. Where the driving shaft 16 for the roll extends through the wall a stuffing box 17 is provided to prevent paste exuding at this point. At the other end of the shaft a cover plate 18 is provided.

The roll 13 is adapted to transfer paste directly to a paste applying disc 19 and accordingly the surface of the roll is concaved to be complementary to the circumference of the disc. Between such concave portion 20 and the ends of the roll, the surface of the roll is bevelled off at 21 so that the rims 22 of the end walls of the roll do not come into contact with the pasting disc 19. By such arrangement any paste that may exude between the ends of the roll and the walls of the box will not be transferred to the pasting disc.

Below the transferring roll the box is formed with a bottom plate 23 having an upper surface complementary in shape to the surface of the roll and extending a substantial distance around the roll, for example about 90°, equally arranged on either side of the vertical.

This plate 23 is arranged in close contact with the roll so that the egress of paste between the plate and roll is prevented. The plate 23 may be separate from the wall 11 of the box and may be adjustable or may be positively fixed in position by pins 23a after adjustment in assembling.

The rotation of the roll 13 is such that the roll surface moves inwardly with respect to the plate 23 so that any paste on the roll after passing the pasting disc, will be carried into the box. As an aid to this action the outer edge of the plate 23 adjacent the roll may be bevelled off.

An adjustable plate 23b may be located at the outer side of the plate 23.

Above the roll 13 an adjustable gate or wall 24 is provided which forms the front wall of the box. The gate is mounted to slide in guides 25 and at its lower edge is shaped to agree with the contour of the roll. The gate is adjusted by the screw 26 relatively to the roll 13 to provide the desired feed of paste. The gate is provided with an orifice 27 (or a plurality thereof) which insures a constant feed of paste to the roll 13 even when the gate is in close contact with the roll.

Above the box and detachably secured thereto is a paste reservoir 28 which is of circular cross section and accommodates a plunger 29 by which pressure is applied to the paste to feed it to the

transfer roll 13. The plunger is provided with a rod 30 extending through the upper end of the reservoir and to which a downward thrust is applied by any suitable means. For example a pivoted weighted lever 31 may be provided with a pawl 32 adapted to engage in ratchet teeth 33 formed in the plunger rod whereby the plunger is pressed downwardly.

The upper part of the paste box 10 may be of circular shape to agree with the cylindrical reservoir 28 whereby the plunger may extend into the box in feeding the paste, if desired.

The reservoir 28 may be provided with a projecting rim adapted to seat within a recess in the upper part of the box 10 and suitable thumb screw fastenings 34 are provided for holding the reservoir in position on the box.

The paste supplying apparatus together with the paste applying disc 19 are mounted for adjustment as a single unit so that the adjustment 20 of the pasting disc relatively to the running web may be obtained, whereby the relative disposition 15 of the feeding roll 13 and the pasting disc 19 are maintained.

For this purpose a mounting 35 (see Figure 5) 25 is provided upon which the parts are mounted and in which the gearing 36 is located for driving the shaft 16 and the pasting disc 19.

The mounting 35 has a depending sleeve 37 30 located in a bearing 38 carried by the framing of the machine to which the apparatus is applied.

A driving spindle 39 extends through the sleeve 37 and is provided with a gear 40 which meshes with a driving gear 41 which is driven from any 35 suitable part.

The driving gear 41 is of a depth sufficient to allow for a suitable vertical adjustment of the spindle 39 and the sleeve 37. This vertical adjustment is effected by an adjusting spindle 42 40 which has a screwed part 42a engaging a fixed step 43. Rotation of the spindle 42 is effected by the gear 44, 45 provided with a handle 46.

Suitable driving means are provided for rotating the transfer or feed roll 13 and the paste 45 applying disc 19.

We claim:

1. An apparatus for applying paste to a moving surface such as the wrapper web of a cigarette rod machine, comprising a paste container 50 having an outlet, a paste applying disc, a paste feeding roll located in said outlet and having a peripheral portion protruding through the outlet for transferring paste directly to said paste applying disc, means for rotating said feeding 55 roll, means for applying pressure to the paste in the container to feed it to said roll, said apparatus including also an adjustable gate ele-

ment above the plane of the disc and co-operating with the periphery of the roll for controlling the feed of the paste over the roll to the disc; and a bottom plate conforming and closely adjacent to the surface of the feed roll over a substantial 5 arc, preventing egress of paste when in place, said plate being removable to give access to the container and to expose the entire bottom surface of the roll while the roll and gate remain in place.

2. An apparatus for applying paste to a moving surface such as the wrapper web of a cigarette rod machine, comprising a paste container having an outlet, a paste applying disc, a plain surfaced feeding roll located in said outlet for 15 transferring paste directly to said paste applying disc, said roll having a concave surface complementary to the curvature of the paste applying disc, a shaft for rotating said roll, means for applying pressure to the paste in the container, 20 an adjustable gate element for controlling the feed of the paste to the roll, bearing cheeks on said shaft and adapted to abut the ends of said roll, and means to set said cheeks up against the sides of said roll.

3. An apparatus for applying paste to a moving surface, as claimed in claim 2 wherein the surface of the roll on either side of the concave portion is beveled to prevent paste on the ends of the roll being transferred to the disc, and a 30 bottom plate which conforms to said concave and beveled portions.

4. An apparatus for applying paste to a moving surface as claimed in claim 2 wherein the container is provided with a bottom plate conforming and closely adjacent to the surface of the feed roll over a substantial arc, being formed with a ledge projecting below the disc and providing a trough with a closure conforming to the roll surface and removable while the bottom 40 plate remains in place.

5. An apparatus for applying paste to a moving surface as claimed in claim 2 wherein a paste reservoir is removably mounted on, and directly over, the container, said reservoir being provided with piston means for feeding paste under pressure to the roll, said container being formed with a rear wall curved concavely relatively to the direction of pressure feed, to bias the paste directly against said roll, and a bottom plate 50 formed separately from said rear wall and mounted in continuation thereof below the roll, being removable readily to give access to substantially the entire lower periphery of the roll while the latter remains in place.

ROBERT JOHN ALEXANDER CHANDLER.
JOHN CRIGHTON.
